BACK SPLASH PANEL UNIT FOR A COOKING RANGE

Lawrence H. Wilson, Detroit, Mich.

Application April 9, 1956, Serial No. 40,967

Term of patent 14 years

(Cl. D81—25)

Fig. 1 is a perspective view of a back splash panel unit for a cooking range embodying my new design; and Fig. 2 is a side elevational view thereof.

The side not shown in Fig. 2 is similar to the side shown therein.

The essential features of my new design reside in the portions shown in full lines.

I claim:

The ornamental design for a back splash panel unit for a cooking range, as shown and described.
